WILLIAM CHRISTOPHER SCHÖPPNER, OF ASTORIA, NEW YORK.

PROCESS AND APPARATUS FOR REFINING CHOCOLATE AND THE LIKE.

1,390,251.

Specification of Letters Patent. Patented Sept. 6, 1921.

Application filed July 2, 1920. Serial No. 393,630.

To all whom it may concern:

Be it known that I, WILLIAM CHRISTOPHER SCHÖPPNER, a citizen of the United States, residing at Astoria, Long Island, 5 in the county of Queens and State of New York, have invented new and useful Improvements in Processes and Apparatus for Refining Chocolate and the like, of which the following is a specification.

10 This invention relates to a process and apparatus for refining chocolate and the like.

The refining, to which this invention is directed, is a super-refining and is intended to produce extra smooth chocolate. For example, the product is especially suitable for 15 milk chocolate and very high grade coatings. High grade chocolate has been produced heretofore, but the processes adopted are relatively slow compared to the process 20 of this invention. As a representative example of prior practice in the production of high grade chocolate, the liquor, after it has been subjected to the ordinary refining, as by disk or roll refiners, is treated in the 25 conge, or Swiss rubbing machine. This machine, which consists of a heavy roll reciprocable along a granite bed, requires, as a general rule, from forty-eight to seventy- 30 two hours to obtain the desired result.

35 My invention, broadly, is concerned with, and has for its object the provision of, a process and apparatus for refining chocolate and the like which will produce a product of a quality equal to that obtained by prior processes, but in a much shorter time.

The process, broadly considered, consists 40 in placing the liquor in a suitable receptacle and in rapidly and repeatedly driving the liquor against roughened surfaces, whereby the particles of the liquor are caused to 45 impinge upon and flow over such surfaces many times for the refining action.

As another feature of the process, the liquor may be subjected to a churning action 45 at the same time that it is being driven against the roughened surfaces, which not only continually stirs the liquor and keeps it in thoroughly amalgamated condition but also aids in the refining action by driving 50 the liquor along, as well as against, the roughened surfaces.

In carrying out the process, I prefer to make use of an apparatus, involving a suitable liquor containing receptacle, which is 55 provided with roughened surfaces, and one

or more propeller-like members which, by their rotation, are arranged to drive the liquor against the roughened surfaces of the receptacle.

As another feature of the apparatus, I 60 may roughen the propeller-like members themselves to increase the refining action.

In the preferred form of the apparatus, the roughened surfaces of the receptacle are arranged in a plane normal, or substantially 65 so, to the axis of revolution of the propeller members but, as an added feature of the apparatus, I may provide roughened surfaces in planes parallel to such axis, as about 70 the side or sides of the receptacle.

75 My refining apparatus is also advantageous in that it may function advantageously as a means for tempering the liquor after it has been refined. Generally, the liquor, after having been refined, as in the conge, 80 is then transferred to a mixing kettle where it is stirred and kept from separating until ready for use. With my apparatus, it is unnecessary to transfer the liquor to a mixing or tempering kettle for, after the refining 85 is completed, the propellers may be turned, although preferably at considerably slower speed, to keep the liquor in thoroughly amalgamated condition until ready for use.

85 Other features of the invention will appear in the following description and in the accompanying drawings, wherein I show an apparatus which embodies the structural features of the invention and is suitable for 90 use in carrying out the process.

In these drawings,—

Figure 1 is a sectional elevational view of the apparatus; and

Fig. 2 is a sectional plan view thereof, 95 drawn to a reduced scale.

Referring to these drawings, the apparatus, in its broadest aspects, involves a suitable receptacle *a*, in which the liquor to be refined is placed and which is provided with 100 roughened surfaces, as shown at *b*, and suitable means for rapidly and repeatedly driving the liquor against these surfaces. Preferably, such means consist of one or more rotatable propeller-like members *c*, which 105 are arranged to rotate about an axis substantially normal to the plane in which the roughened surfaces *b* are located. Preferably also, the receptacle *a* is surrounded, as far as may be, by a heating jacket, as *d*, 110

through which a suitable heating medium, such as steam, hot water, or a mixture of both, is circulated by means of pipes *e*.

In carrying out the process, the chocolate liquor, or like substance to be treated, is placed in the receptacle *a*, wherein it is maintained at proper temperature by means of the heating medium flowing through the jacket *d*, and the member or members *c* are rotated at relatively high speed. The members *c* are shaped substantially like propellers and so function, except of course that, since they are held from axial movement, the liquor rather than the propellers move in the direction of the axis of rotation. The direction of rotation of the propellers is such as to force the liquor toward and against the roughened surfaces. By this action, I conceive that each particle of the liquor is caused to impinge again and again on the roughened surfaces *b* and to move over such surfaces and over and against the other particles of the liquor, whereby such particles are smoothed and the liquor refined.

The propellers *c* likewise cause the liquor to flow along, as well as against, the roughened surfaces *b*, and thus increase and expedite the refining action. The rotating propellers also circulate the liquor to insure that all portions thereof are subjected to the refining action and they also serve, by their stirring action, to keep the liquor in a thoroughly amalgamated condition. The eddies and various currents set up by the rotation of the propellers *c*, by themselves, cause portions of the liquor to repeatedly flow over other portions and thereby, in a measure, refine it. Such method of refining is, however, relatively slow, and my process is characterized by the repeated forcing of the particles of the liquor against, over, and along roughened surfaces, which very materially lessens the time necessary to secure the desired results. As compared to prior practice, as with refining in the conge for example, my process requires only from one-fourth to one-sixth of the time formerly necessary for a given degree of refining.

Preferably, in order to accelerate the process, those surfaces of the propellers adjacent to the roughened surfaces *b*, are themselves roughened as at *f*. Furthermore, additional roughened surfaces may be provided in the receptacle *a* for like reasons as, for example, about the sides thereof as conventionally indicated at *g*.

As to the details of the illustrated apparatus, the roughened surfaces *b* are, as shown, preferably formed on separate members which are inserted in the receptacle *a*. Thus, four sector-shaped blocks *h* are applied to the bottom of receptacle *a*, the upper surfaces of which blocks have previously been roughened, as by corrugating, although

the particular character of the roughened surfaces is not necessarily essential. As shown, the corrugations of each sector *h* are arranged at right angles to those of the adjacent sectors, whereby the liquor, when traveling in a horizontal plane, will encounter the roughened surfaces, as well as when directed downwardly. The sectors *h* may be made of any suitable material, such for example as iron or stone.

I prefer to employ at least two propellers *c* and these, preferably, although not necessarily, rotate in opposite directions. Each propeller *c* is fixed to the lower end of a vertical shaft *i*, which is rotatably mounted in suitable bearings *j* carried by a cover *k*, removably secured to the top of receptacle *a*, and provided with openings, as *l* for the introduction of the liquor into the receptacle. Collars *m* fixed to each shaft *i* hold the latter from axial displacement in either direction and take the thrust of the propellers *c*. A horizontal shaft *n*, rotatably mounted in cover *k* slightly in back of the shafts *i*, is arranged to drive both of the latter through sets of spiral gears *o* and the two sets of gears are arranged in rights and lefts to drive the shafts *i* in opposite directions. The shaft *n* is the main power shaft and may be driven from a suitable source of power by the pulley shown.

Thus, I have provided an improved process and apparatus for refining chocolate and the like, which is characterized by a substantial reduction in the time necessary to secure a given degree of refining.

The invention has been set forth herein for illustrative purposes, but the scope of the invention is defined by the appended claims rather than by the foregoing description.

What I claim is—

1. The method of refining chocolate and the like, which consists in rapidly and repeatedly driving the chocolate against roughened surfaces.
2. The method of refining chocolate and the like, which consists in placing the liquor into a suitable receptacle, and rapidly and repeatedly forcing the liquor against roughened surfaces therein and thereby causing the particles of the liquor to engage and move over such surfaces to smooth them.
3. The method of refining chocolate and the like, which consists in placing the liquor in a suitable receptacle, in stirring the liquor, and at the same time driving it rapidly in another direction to cause it to impinge upon and flow over roughened surfaces in the receptacle.
4. The method of refining chocolate and the like, which consists in rapidly and repeatedly driving the chocolate against roughened or pocketed surfaces and in utilizing for such refining action a volume of

the chocolate which is considerably in excess of the volume of the pockets in said surfaces.

5. The method of refining chocolate and the like, which consists in placing the liquor into a suitable receptacle having roughened or pocketed surfaces therein, in treating at one time a volume of liquor in excess of the volume of the pockets in said surfaces, and 10 in refining the liquor by rapidly driving it against said surfaces.

6. The method of refining chocolate and the like, which consists in placing the liquor into a suitable receptacle having 15 roughened or pocketed surfaces therein, in treating at one time a volume of liquor in excess of the volume of the pockets in said surfaces, and in refining the liquor by rapidly driving it against said surfaces, while circulating it and causing it to flow over the surfaces and in and out of the pockets therein.

7. A refining apparatus for chocolate and the like, comprising, a suitable receptacle for 25 the chocolate, roughened surfaces provided in the receptacle, and driving means out of contact with said roughened surfaces for repeatedly forcing said chocolate thereagainst.

30 8. A refining apparatus for chocolate and the like, comprising a suitable receptacle for the chocolate, roughened surfaces provided in the receptacle, and agitating means in the receptacle out of contact with said roughened surfaces constructed so as to repeatedly drive the chocolate against the latter to refine the chocolate.

9. A refining apparatus for chocolate and the like, comprising, a suitable receptacle for 40 the chocolate, roughened surfaces provided in the receptacle, and agitating means in the receptacle out of contact with said roughened surfaces constructed so as to repeatedly drive the chocolate against the latter to refine the chocolate, said agitating means having roughened surfaces to increase the refining action.

45 10. A refining apparatus for chocolate and the like, comprising a suitable receptacle for the chocolate, roughened surfaces provided in the receptacle, and a propeller-like member in the receptacle out of contact with said roughened surfaces to repeatedly force the chocolate thereagainst.

55 11. A refining apparatus for chocolate and the like, comprising, a suitable receptacle for the chocolate, roughened surfaces provided in the base of the receptacle, and a propeller-like member rotatable in a plane substantially parallel to the bottom of the receptacle but out of contact with said roughened surfaces and constructed so as to repeatedly force the chocolate against the latter.

60 12. A refining apparatus for chocolate and the like, a suitable receptacle for the choco-

late, roughened surfaces provided in the base of the receptacle, and a pair of propeller-like members rotatable in opposite directions but out of contact with said roughened surfaces and each constructed to force the chocolate downwardly against the latter. 70

13. A refining apparatus comprising a suitable receptacle for the liquor having on its inner surface refining or reducing plates and means spaced from the latter to force 75 the liquor against and across the face of said plates.

14. A refining apparatus comprising a receptacle for the liquor, a reducing or refining disk at the bottom of the receptacle and means spaced from said disk to force the liquor against and across the face of the latter.

15. A refining apparatus comprising a liquor containing kettle, having an interior 85 refining surface and means out of contact with said surface to force the circulation of a mass contained in the kettle directly against and across the face of said surface.

16. A refining apparatus comprising a 90 mixing kettle, and relatively movable refining means having suitable refining surfaces thereon and within the kettle and spaced from one another to cause a rapid rubbing action of the liquor against itself 95 and against said surfaces.

17. A refining apparatus comprising a kettle provided at the bottom with a roughened refining surface and means spaced from the latter to drive the liquor within the kettle 100 forcibly against and over said surface.

18. An apparatus for the purpose described comprising a kettle with the inside bottom surface constructed as a reducing disk and a propeller mounted within the 105 kettle and out of contact with said disk and means to drive the propeller with sufficient speed to force the liquor to rub over said surface.

19. An apparatus for the purpose described comprising a kettle having an interior reducing surface and two or more propellers rotatable in opposite directions out of contact with said surface to violently agitate liquor in the kettle and force it over 115 the said surface.

20. An apparatus for the purpose described comprising a kettle, liquor propulsion means therein arranged to cause a circulation downwardly and around the bottom of the kettle, and a reducing surface on the bottom of the kettle out of contact with said means. 120

21. An apparatus for the purpose described comprising a kettle having angularly arranged reducing surfaces, two or more oppositely rotatable propellers mounted to lie within the kettle out of contact with said surface and held against vertical movement along axes arranged away from the 125 130

kettle axis, and means to drive said propellers to thereby force liquor in the kettle with substantial force against said surfaces.

22. The combination of means provided
5 with a chocolate reducing surface and a ro-
tatable propeller held out of contact with the
latter and against axial movement to force
an otherwise free mass of liquor against and
over said surface.
- 10 23. An apparatus for the purpose de-
scribed comprising a kettle having at its
bottom reducing surfaces, two propellers ro-

tatable in opposite directions about axes
parallel to the kettle's axis and spaced equi-
distantly from the latter, said propellers 15
arranged to rotate out of contact with said
surfaces and to drive the liquor in the kettle
downwardly against said surfaces to refine
it, and reducing surfaces provided on the
driving sides of said propellers.

20 In testimony whereof I have affixed my
signature.

WILLIAM CHRISTOPHER SCHÖPPNER.
